MEANS FOR PROTECTING THE RETORTS OF
STOKERS AGAINST HIGH TEMPERATURES

Ross C. Johnson, Dayton, Ohio

Application July 31, 1937, Serial No. 156,805

2 Claims. (Cl. 110—45)

This invention relates to new and useful improvements in means for protecting the retorts of stokers against high temperatures.

It is one of the principal objects of my invention to provide a fire box having means such as a plate for protecting the retorts of stokers, and more particularly those stokers which are used in brick, tile and pottery kilns, annealing furnaces, bake ovens and other structures from exposure to the extremely high temperatures prevailing in such furnaces. In a brick kiln for instance, the fire box temperature, which averages about 5500 degrees Fahrenheit, would soon burn out the retort and tuyères of a stoker employed to deliver fuel and air to the kiln. The plate structure which I apply to the retort, however, will protect it against such high temperatures by permitting atmospheric or other air or water to circulate around the bottom of the retort without interfering with the forced draft which issues from the tuyères.

Other important and incidental objects will be brought out in the following specification and particularly set forth in the subjoined claims.

In the accompanying drawing illustrating my invention, Figure 1 is a top plan view of the retort of a mechanical stoker showing my protective means applied thereto. Figure 2 is a sectional view taken through the fire box showing my retort protective means mounted therein. And Figure 3 is a sectional view taken through said fire box at right angles to the section illustrated in Figure 2.

Referring to the accompanying drawing, for a detailed description of my invention, the numeral 1 designates the hopper, 2 the feed tube and 3 the retort of a conventional mechanical stoker. Within the retort are tuyères 4 which receive a forced draft from an air tube 5.

The tubes 2 and 5 project into the ash pit 6 of a fire box 7 to bring the retort 3 and its tuyères 4 in a proper position therein to discharge fuel and air thereto.

In order to protect the retort and tuyères against the extremely high temperatures encountered in brick, tile and pottery kilns for example, I provide a metal plate which, in the present instance, is made in sections. One section 8 of this plate is mounted in the fire box 7, at one side of, and a short distance below, the retort 3, upon members such as I-beams 9, 9 on the floor of the ash pit 6. To this stationary section 8 of the plate, there are hingedly connected two sections 10 and 11 which are concaved at their

inner edges to fit against the curved wall of the retort 3.

The free end of each hinged or swinging plate section has on its bottom surface a projection 12 pivotally connected by a link 13 to the inner end 5 of a longitudinally movable operating rod 14 carrying a handle 15 on its outer end. Each rod 14, which is supported for longitudinal movement by a bracket 16 secured to the fire box wall, is pivotally connected to the free end of its respective link 13 and to another link 18 that is pivotally secured at its lower end to a bracket 19 on the concrete floor of the ash pit.

When the operating rods 14 are forced inwardly, they will raise the plate sections 10 and 11 15 to the level of the stationary section 8, to form around the retort 3, a short distance below its top, a protective surface upon which refractory material such as silica (not shown) may be placed. Now, the atmospheric air which enters 20 the ash pit 6 will be prevented by the plate from leaving the top of the fire box 7, whereupon said air will circulate around the bottom of the retort to cool it so that it will not be fused or melted by high temperatures. Since the plate is 25 below the top of the retort and the outer openings of the tuyères, it will not interfere with the forced draft discharged by the latter.

When it is desired to dump slag or clinkers from the protective plate, the two sections 10 and 30 11 thereof may be lowered by pulling the operating rods 14 outwardly to break the links 13 and 18.

I do not desire to be limited to the details of construction and arrangement herein shown and 35 described, and any changes or modifications may be made therein within the scope of the subjoined claims.

Having described my invention, I claim:

1. In stoker apparatus of the class described, 40 the combination with a fire-box having an opening in the base thereof to atmosphere, and a retort therein spaced from the walls of said box and having tuyère openings in the upper portion thereof, of a partition member extending 45 across the fire-box between the tuyère openings of the retort and the air opening of the fire-box and dividing the fire-box into a combustion chamber and a cooling chamber, said partition comprising a stationary section having a dumping door therein for establishing communication between the combustion chamber and the cooling chamber, and means extending outwardly of the fire-box for operating the door to open and close 50 the same.

2. In stoker apparatus of the class described, the combination with a fire-box having an opening in the base thereof communicating with the atmosphere, and a retort therein spaced from the walls of said box and having tuyère openings in the upper portion thereof, of a partition extending across the box between the tuyère openings and the air opening of the fire-box for dividing said fire-box into a combustion chamber and a cooling chamber beneath the

same with which said air opening communicates, said partition having a stationary section and downwardly opening movable sections, means for supporting the stationary section and means for supporting and operating the movable sections, 5 said last-named means comprising a toggle device and an operating lever extending through the walls of the fire-box.

ROSS C. JOHNSON.
